INVENTOR
William Thomas McDuffee
BY *F. J. Smith*
ATTORNEY

UNITED STATES PATENT OFFICE.

WILLIAM THOMAS McDUFFEE, OF PENSACOLA, FLORIDA.

AUTOMATICALLY-OPERATED SAFETY GATES.

Application filed January 6, 1925. Serial No. 783.

To all whom it may concern:

Be it known that WILLIAM THOMAS McDUFFEE, a citizen of the United States, residing at Pensacola, Escambia County, State of Florida, has invented certain new and useful Improvements in Automatically-Operated Safety Gates, of which the following is a full, clear, and exact description.

The present invention relates generally to automatic safety devices and is more especially directed to improvements in gates for railroad crossings and other places where safeguards of this type may be found necessary or desirable.

For the purposes of the present disclosure, I shall describe my invention in a specific application, that is, as used in the protection of a railroad grade crossing.

As is well known, various forms of automatically actuated protective devices have been devised for those railroad crossings in outlying sections where the cross traffic does not warrant the cost of maintenance of manually operated gates or a watchman or a signalman. These usually have been operated electrically or hydraulically and have been of a more or less complicated construction with the attendant lack of dependability in operation. Owing to the high cost of installation and maintenance, the latter involving the employment of skilled labor in supervision and inspection, protective devices of the aforesaid types have not been generally adopted to any appreciable extent by the railroad organizations.

The general object of the present invention is to provide an automatically operating mechanism for lowering and raising the gates at railroad grade crossings, which will overcome the objections to present types of structures in a simple and economical manner.

It is a further object of my invention to provide a gate for railroad crossings, together with mechanism for automatically controlling the functioning thereof, which will embody a relatively small number of elements so associated as to insure dependability in operation.

My invention further contemplates a railroad crossing gate which is mechanically operated to lowered or raised position by the approaching or passing train wherein the cost of installation and maintenance is comparatively small, competent supervision

being within the province of the ordinary section hands.

Other objects and advantages flowing from the use of my invention will present themselves as the description proceeds, and I would have it understood that I reserve unto myself all rights to the full range of equivalents, both in structure and in use, to which I may be entitled under my invention in its broadest aspect.

In order to present a clear disclosure of the method of practicing my invention, I have elected to illustrate and describe a preferred embodiment thereof, as applied to the protection of a grade railroad crossing, wherein a single line of track is used for traffic in both directions. It will be obvious, however, that changes in details of structure and arrangement of parts may be made without departing from the spirit and scope of my invention as defined by the appended claims.

In the accompanying drawings:

Figure 1 is a side elevation of a section of track with crossing gates and actuating mechanism made in accordance with my invention associated therewith.

Figure 2 is a plan view of the structure shown in Figure 1, the gates being in lowered position.

Figure 3 is an enlarged view, in perspective, of the gate lowering mechanism.

Figure 4 is a similar view of the mechanism for raising the gate.

Figure 5 is a section on the line 5—5 of Figure 2.

Figure 6 is a section on the line 6—6 of Figure 5, and

Figures 7 and 8 are sectional details on the lines 7—7 and 8—8 of Figure 2.

Referring now to the drawings in detail, in which like characters of reference are employed to designate similar parts throughout the several views, 10 indicates the usual rails which are laid upon and spiked to the ties 11 in accordance with established practice.

The gate 12, which is preferably of the counterbalance type having the dependent guards 12^a, is located at the side of the track so as to obstruct or close the crossing when lowered, by the rotation of its supporting shaft 13 in the bearings 14 carried on the top of the base or standard 12^b, in the manner hereinafter described.

The lowering of the gate 12 is designed to be effected when the approaching train is several hundred feet from the crossing to be protected, and to this end I provide an actuating mechanism which is adapted to be functioned by the pilot wheels of the locomotive, the gate remaining in lowered position until the rear truck of the last car passes a predetermined distance beyond the crossing.

The aforesaid actuating mechanism comprises a trigger 15 which is pivotally mounted at 16 within a recess 17^a provided in the rail section 17, as clearly shown in Figure 5.

Having bearings in the opposite walls of the recessed rail section and below the trigger 15, is a short shaft 18, the intermediate portion of which is offset or in the form of a throw 18^a. Mounted on the outer end of the aforesaid shaft 18, to rotate therewith, is a forked or bifurcated member 19 having its arms 20 and 21 disposed in a plane parallel to that of the shaft 18.

Pivotedly connected to the arm 20 at 22, is a rod 23 reciprocal within the sleeve 24, the said rod carrying an expansion spring 25 the ends of which bear against the head of the sleeve 24 and the shoulder 23^a of the rod 23. A link or rod 26, fixed to the sleeve 24 as by pins 27 or the like so as to be in effect integral therewith, parallels the rails for operative connection to the throw 28 of the transverse shaft 29 which is connected to the gate shaft 13 through the medium of the links 30, 31 and 32, the latter of which functions as an equalizer and embodies a sleeve 33 fixed to the rod 34, a spring 35 being interposed between the inner shouldered end 36^a of the rod 36, sliding within the sleeve, and the bottom of the latter.

Disposed transversely of the track and having bearings in the trigger housing rail section 17 and its opposite rail section 37, which, like rail section 17, is recessed at 37^a, is a shaft 38, the end thereof which extends outwardly of the rail section 17 being provided with an upwardly and forwardly directed offset forming a hook 39. The other end of said shaft 38, which projects beyond the rail section 37, is likewise offset as shown at 40, a throw 41 being formed in said shaft which is located for movement within the recess 37^a of the rail section 37. (See Figure 2.)

A trigger 42, which may be termed the release trigger, to differentiate from the function of the trigger 15 whereby the lowering of the gate is effected, is pivotally mounted within the slot or recess 37^a of the rail section 37, its free end, similarly to the trigger 15, having a chamfered top surface, this trigger being adapted to engage the throw 41 of the shaft 38 to rock the latter in opposition to the spring 43 fixed to the arm 44 of the offset 40 and anchored to one

of the ties as shown at 45. A spring 46, connected to the arm 20 of the bifurcated member 19, the function of which will hereinafter become apparent, is likewise positively secured to a tie 11, as at 46^a.

The structure thus far described is shown at the left hand side of Figures 1 and 2 of the drawings and embodies the gate lowering mechanism actuated by a train moving in the direction of the arrow A and the means whereby the gates are permitted to rise or ascend after a train moving in the opposite direction passes the protected crossing.

The mechanism adapted to be actuated by the aforesaid triggers 15 and 42 is duplicated at the right hand side of Figures 1 and 2, the triggers 47 and 48 corresponding to the triggers 15 and 42 respectively in construction and in function.

It will be observed that a rod 49 connects the extension 44 of the shaft 38 actuated by the trigger 48 to the outwardly disposed throw 50 of the transverse shaft 51, while the throw 52 at the other end of said shaft 51 is linked to the extension 44 of shaft 38 associated with the trigger 42, by a rod 53.

Assuming that a train is approaching the crossing in the direction of the arrow A, the pilot wheels of the locomotive on successively coming in contact with the normally angularly disposed or inclined triggers 15 and 42 will depress them within their respective rail sections, the depression of the trigger 15 causing it to engage the throw 18^a and rock the shaft 18. This results in an arcuate movement of the arm 20 of the bifurcated member 19 in an upward direction which exerts a pull upon the rod 26 connected to the throw 28, and effects the lowering of the gates, through the medium of the common cross shaft 29 and the connecting linkage, the yieldable connection between the rods 23 and 26 compensating for any sudden thrusts or jars imposed upon the mechanism and insuring a steady movement of the gates to their ultimate position.

As the trigger 42 is depressed, the shaft 28, the throw 41 of which is engaged thereby, is rotated against the tension of the spring 43, whereby the arm or extension 44 moves upwardly through a short arc and pulls the rod 53. This movement of the rod 53 rocks the shaft 51 which, in turn, through the medium of the connection 50, delivers a thrust to the rod 49 which rotates the shaft 38^a to bring the hook 39^a adjacent the trigger 47, into engagement with the depressed arm 21^a, the gates being thereby positively locked in lowered position until released by the passage of the train.

As the trigger 48 is depressed by the wheels traversing the same, the shaft 38^a will be rocked to raise the hook 39^a out of

- engagement with the arm 21^a of the gate actuating mechanism, the hook 39 at the opposite side of the crossing engaging the arm 21. Assuming that the train has now 5 passed the crossing, it will be apparent that the trigger 48 will be freed of pressure prior to the release of the trigger 47 and under the influence of the spring 43, the hook 39 will become disengaged from the arm 21, permitting the gates to rise, as said trigger 47 10 is released, the springs 46 and 46^a, in conjunction with the counterbalance weights 12^c carried on the gates 12, will cause the latter to ascend with a smooth steady 15 motion, it being obvious that the equalizing device embodied in links 32, combined with the previously described yieldable connection between the rods 23 and 26 will positively control or govern the descent or ascent 20 of the gates in a manner which will insure them against damage which might result from shocks or jars transmitted thereto through the sudden movements of the actuating mechanism.
- 25 With a train moving in the opposite direction, that is from the right of Figures 1 and 2, the sequence of operation will be reversed, it being manifest that irrespective of the direction of movement of the trains, the 30 gates are lowered and positively maintained in lowered position during the entire period in which the train is within the limits of the control mechanism.
- While I have described my invention with 35 reference to the specific structure shown, it will be manifest that in lieu of locating the triggers 15 and 42 and their counterparts 47 and 48 within the rail sections, they may be supported alongside of the ordinary rail, 40 such as shown at 10, in a manner to be engaged and depressed by the wheels passing thereover. In such an event, slight changes in the method of producing rotary movement of the shafts 18 and 38 to obtain 45 the described results will be necessary. These, and similar changes, however, clearly fall within the scope of my invention as set forth in the following claims.
- I claim:
- 50 1. The combination with a railroad track of crossing protecting gates and means for automatically lowering said gates, said means comprising a recessed rail section having a trigger pivotally mounted therein 55 for engagement by the wheels of a train unit and interconnected rotatable and reciprocable members connecting said trigger to the gates, whereby the pivotal movement of said trigger under pressure will actuate 60 said members to effect the lowering of the gates and means operable independently of said gate lowering mechanism to lock the gates in lowered position.
- 65 2. The combination with a railroad track of crossing protecting gates and means for 70 automatically lowering said gates, said means including a recessed rail section having a trigger mounted for movement relative thereto and adapted for engagement by the wheels of a train unit, interconnected 75 rotatable and reciprocable members connecting said trigger to the gates, whereby the movement of said trigger under pressure will actuate said members to effect the lowering of the gates, means operable independently of said gate lowering mechanism to lock the gates in lowered position and means operated by the train unit traversing the same to render said locking means 80 ineffective and permit the gates to ascend.
3. The combination with a railroad track of crossing protecting gates and means for automatically lowering and raising said gates, said means comprising a recessed rail section, a trigger pivotally mounted therein for engagement by the wheels of a train unit, a counterbalanced gate located on each side of the track, said trigger being distant from said gates, a device associated with the track for engagement by said trigger, means for operatively connecting said device to both of said gates whereby the movement of the trigger under pressure will actuate said device to transmit motion through said connecting means to lower the gates, means 85 functioned by the movement of the train unit along the rails to lock the gates in lowered position and means, including a weight actuated trigger, for releasing said locking means and permit the gates to 90 ascend.
4. The combination with a railroad track of grade crossing gates, and means for automatically lowering and raising said gates, said means comprising a recessed rail section, a trigger pivotally mounted therein and having a portion normally projecting in the path of a wheel traversing said rail section, means of connection between said trigger and the gates, said means including rigid rotatable and reciprocable members, whereby the depression of said trigger will 95 actuate the gates to lowered position, yieldable elements associated with said connecting means for cushioning the movement of said mechanism and the gates under predetermined conditions, and mechanism operable independently of said gate actuating means for locking the gates in lowered position, said mechanism being automatically operable to release the gate actuating means for movement of the gates to raised position when their actuating triggers are relieved of pressure.
- 100 5. The combination with a single railroad track having grade crossing gates associated therewith, of mechanism for actuating said gates to lowered and raised positions adapted to be functioned by a train passing over 105 said track in either direction, said mecha-

nism comprising a pair of recessed rail sections located on each side of the crossing and distant therefrom, a trigger rockably mounted within each of said sections, means of connection between the gates and a trigger on each side of the crossing, said means embodying rigid rotatable and reciprocable members, whereby the depression of either of said latter triggers by a train or the like approaching the crossing, will actuate said connecting means to lower said gates, and means connected to the remaining trigger on each side of the crossing for locking the gates in lowered position, the depression of the locking trigger first engaged by the wheels of the vehicle traversing the rails, effecting the locking of the gates in lowered position, the gate actuating mechanism being released for raising the gates, as the locking mechanism trigger at the opposite side of the crossing is relieved of the pressure of the vehicle traversing the rails.

6. The combination with a single track of a railroad having grade crossings, of protective gates for said crossings and means controlled by the movement of a vehicle along said track for raising and lowering said gates, said means comprising mechanism embodying a pressure actuated element located on each side of a crossing and distant therefrom, and mechanism for locking the gates in lowered position, said locking mechanism including pressure actuated elements disposed on each side of said crossing and distant therefrom, said gate actuating and locking mechanisms being adapted to be functioned sequentially to lower and lock said gates in lowered position by a vehicle approaching the crossing from either direction upon said track, the gates being released and successively raised when the vehicle has traversed the crossing.

WILLIAM THOMAS McDUFFEE.
